CLIFTON F. LEATHERBEE, OF NEWTON, MASSACHUSETTS, ASSIGNOR TO PAINTING MACHINE COMPANY, OF KITTERY, MAINE, A CORPORATION OF MAINE.

CONVEYER.

1,241,525.

Specification of Letters Patent.

Patented Oct. 2, 1917.

Original application filed April 4, 1910, Serial No. 553,830. Divided and this application filed August 17, 1910. Serial No. 577,624.

To all whom it may concern:

Be it known that I, CLIFTON F. LEATHERBEE, a citizen of the United States, residing at Newton, in the county of Middlesex and 5 State of Massachusetts, have invented certain new and useful Improvements in Conveyers, of which the following is a specification.

The present invention relates to conveyers and more especially to the provision of an improved form of apparatus which may be employed in handling and disposing of material of considerable length, such as flooring, strips of molding, cross-arms and like 10 strips or lengths of material issuing from the machine adapted for the application of paint, stain, varnish, creosote or preservative substance, coating of insulation material and the like. 15 The principal objects of my present invention are the provision of a machine characterized as above noted, which is adapted to receive the treated material as it issues from the treating or coating machine and 20 convey it either forwardly or laterally to a drying apparatus or other means of disposition; to provide improved means for removing the treated material from the machine and keep it exposed to the atmosphere 25 for a certain period of time to the end that it may be more readily handled; to provide means for preventing, as far as possible, contact of the treated material with the conveyer and consequent marring of the treated 30 surface or soiling of the conveyer, or both; the provision of improved means for transferring the material from the conveyer moving in one plane to that of a conveyer moving in another plane, as well as certain 35 further objects as will hereinafter more fully appear. Other features of my present invention are more fully set forth and claimed in my co-pending application Serial No. 553,830, filed April 4, 1910, of 40 which this is a division.

In the attainment of the objects above set forth, together with such additional ad-

vantages as may be below disclosed, I have provided a construction, preferred embodiment of which is illustrated in the accompanying drawings, wherein—

Figure 1 is a plan view of a preferred form of conveying and elevating mechanism utilized by me; and

Fig. 2 is an end elevational view of a portion of the apparatus of Fig. 1, part of such apparatus having been removed and part being shown in section taken on the line II—II of Fig. 1, and

Fig. 3 is an elevational view of a detail of construction.

Referring now more particularly to Fig. 1, it will be observed that I have shown my improved conveyer arranged for use in connection with a coating machine indicated diagrammatically at 3, arranging at one end 65 of such coating machine a belt conveyer 4 and at the opposite end of the conveyer 4 a secondary belt conveyer 5 parallel to which is placed an elevating conveyer 6, to the end 70 that as the treated material issues from the machine 3, it is deposited on one end of the belt conveyer 4, thence discharged upon the secondary belt conveyer 5 disposed on a lower plane, and thence delivered to the elevating conveyer 6, in order that delivery of the material from the machine upon the drier conveyer 21 may not interfere with the action of the device by means of which the attendant of the machine 3 removes the 80 material for drying from the conveyer 4 to the conveyer 6.

The belt 5 is provided at intervals with cleats 7—7, preferably of inverted V-shape, disposed transversely thereof, for purposes 85 of preventing contact of the treated surface of the material issuing from the machine 3 with such belt and consequently marring of such treated surface or soiling of the belt, or both, as the material is moved laterally 90 therefrom, and to provide ways upon which the removing device now to be described may slide freely.

The removing device, as may be clearly

seen from the figures, comprises in preferred form a fulcrum hand-lever 10, carrying pivotally mounted thereon an actuating rod 11 which is attached thereto, a connecting bar 12 to which are pivotally mounted the outer ends 13—13 of a plurality of rocking levers 14—14, the opposite ends 15—15 of which levers are attached to a strip 16 disposed longitudinally of the conveyer belt 5 and adapted to be moved transversely thereof in order to remove from such belt the material and deposit it upon the angularly disposed guideways 17 of the elevating and lowering mechanism now to be described.

Referring now more particularly to Fig. 2, it will be observed that from the guide 17 the material passes onto one of the sets of fingers 18 provided at intervals on the longitudinal members 19 (here shown as pipes) supported at each end upon links of the endless chain 20 engaging sprockets indicated at 22—22^a; one of the upper sprockets 22^a (Fig. 2) is driven intermittently from the shaft 23, which has suitable clutch driving connections, to the hub of the sprocket 24 and is driven from the motor 25 of the treating machine through a sprocket 24^a mounted on said shaft 23, a pair of sprockets 63^b—63^c 30 on the shaft 63 which carries the pulling wheel 64^c driving the conveyer 4, a sprocket 63^a on the shaft of the driving motor 25 of the treating machine 3, chains 64^a and 64^b, connecting said several sprockets and the several conveyers and the treating machine 35 being thereby driven in unison.

The sprocket 24 is adapted to drive by means of the chain 25, a sprocket 26 carried on the shaft 27, which in turn by means of a worm 28 drives a gear 29 keyed on the shaft 30, which carries the sprocket 21.

It is to be understood that the pipes 19 are mounted against rotation relatively to the chain 20 by any suitable means.

As is clearly to be seen on viewing Fig. 2, there is disposed oppositely to each of the fingers 18, a finger 32 provided with a bent portion 33, the purpose of such construction being that as the material is turned, during the progress of the elevating mechanism in the direction indicated by the arrow (Fig. 2) and thence drops away from contact with the fingers 18, it is restrained by such fingers 32 from falling or disengagement from the chain until in its descent it comes in contact with the guides 34 and is thence discharged from the elevating and lowering mechanism upon the floor or suitable means for disposing of it.

By virtue of the travel of the treated material and the manner of handling it herein described, it will be apparent that when quick drying liquids are used in treating it such material has an opportunity to be 65 come thoroughly dried by the time it is dis-

charged upon the guides 34 for further disposition; also that it is so discharged with the unpainted side down, and may be moved away for shipment or storage without abrasion of the unpainted portion through contact with the floor.

As a means for giving a step by step movement to the elevating mechanism shown on plan in Fig. 1 and side elevation in Fig. 2, that is, allowing it to move only the distance between two of the series of fingers 18, on a single impulse, I have provided clutch mechanism and operating means therefor whereby the sprocket 24 may be caused to move with the shaft 23 or remain stationary relatively thereto.

This means for imparting intermittent motion comprises as here shown a rocking lever 40 mounted upon the actuating rod 11, at one end as indicated at 41, and at the other end pivoted as indicated at 42 to the clutch actuating rod 43 which terminates in a bifurcated portion 44 engaging a curved collar 45 on the shaft 23. Actuation of the rod 11 in the direction indicated by the arrow (Fig. 1) moves the rod 43 in the direction indicated by the arrow (Fig. 2), forces the collar 45 to the right against the cone 47 mounted in a yoke 46, moving the face of the cone to the right and thereby throwing in the clutch mechanism 48 and fixing the sprocket 24 against rotation on the shaft 23, thus causing such shaft to drive said sprocket 24 and move the conveyer in the direction indicated by the vertical arrow Fig. 2.

For the purpose of allowing a ready automatic opening of the clutch by simple mechanism, the yoke 46 is carried in the support member 59, which has a tripping device 60 pivotally mounted thereon and provided with a screw 61 whereby the angularity of the mounting of the tripping device relatively to the supporting lever may be varied and the respective ends of the fingers 18 and of the guides 17 be brought into position and alined to insure the delivery of the material from the guides to the fingers upon the actuation of the removing device by the lever 10.

To prevent the tripping device from descending to a position where the finger supports 19 would not strike it and throw out the clutch mechanism above referred to, I provide on the supporting member 59 a stop 62, and to insure the disengagement of the tripping device from such finger support, the pivot point 63 should be so located as to free the end of the device 60, when the clutch is thrown out, and allow the device 60 to descend. From the foregoing description it will be understood that when the actuating rod 11 is moved in the direction indicated by the arrow (Fig. 1) the drying mechanism will lift the material resting upon the fingers 18 on the supports 19 and

continue such movement until one of such finger supports contacts with the tripping device 60, when the supporting member 59 will move to the left, the clutch above referred to will be thrown out and the drying mechanism remain inactive until the actuating rod 11 is again moved in the direction indicated by the arrow.

It is believed that apparatus embodying 10 my present inventions, and the mode of operation thereof, will be understood without more amplified or particularized description.

Having thus described my invention and 15 illustrated its use, what I claim as new and desire to secure by Letters Patent is the following:—

1. In an apparatus of the character described, in combination, a pair of conveyers substantially at right angles, one arranged 20 in a horizontal plane and the other arranged in a substantially vertical plane, guide means between the two conveyers, and intermittently movable means arranged for movement transversely of the first mentioned 25 conveyer for removing material bodily laterally therefrom and delivering it to said second conveyer without changing the parallelism of the material to said first mentioned conveyer.

2. In apparatus of the character described, in combination, a conveyer belt having 30 a series of inverted V-shaped cleats extending transversely thereof, said cleats being adapted to support elongated pieces of 35 material which extend parallel with the length of the belt and overlie a plurality of seat cleats, and a member of length greater than twice the distance between the cleats, arranged for movement transversely of the 40 belt and in a plane parallel to the latter, for removing the pieces of material therefrom, without changing the parallelism of the said pieces with respect to the belt.

3. In apparatus of the character described, in combination, a conveyer belt having 45 a series of inverted V-shaped cleats extending transversely thereof, said cleats being adapted to support elongated pieces of material which extend parallel with the length of the belt and overlie a plurality of said cleats, a member of length greater than twice the distance between the cleats, arranged for movement transversely of the 50 belt and in a plane parallel to the latter, for removing the pieces of material therefrom, without changing the parallelism of the said pieces with respect to the belt, and means for imparting rapid and intermittent 55 movement to said member.

4. In an apparatus of the character described in combination a substantially horizontal conveyer, a substantially vertical second conveyer adjacent thereto, intermittently movable means for removing the material laterally from one conveyer to the

other and means for moving the vertical conveyer one step for each movement of said intermittently movable means.

5. In an apparatus of the character described in combination a substantially horizontal conveyer, a substantially vertical second conveyer adjacent thereto, intermittently movable means arranged for movement transversely of said horizontal conveyer for removal of material laterally therefrom and delivering it to said second conveyer, a clutch for said second conveyer thrown into operation by the movement of said intermittently movable means and a trip device for throwing out said clutch 75 after said vertical conveyer has moved one step forward.

6. In an apparatus of the character described in combination, a substantially horizontal conveyer, a substantially vertical second conveyer adjacent thereto, projections 80 on said vertical conveyer adapted to engage the articles to be carried by said conveyer and means for intermittently moving said vertical conveyer the distance between adjacent projections.

7. In an apparatus of the character described in combination, a substantially horizontal conveyer, a substantially vertical second conveyer adjacent thereto, means for 95 removing the material from said horizontal conveyer to the lower end of said vertical conveyer and means for removing the material from said vertical conveyer at the opposite lower side of said conveyer, 100 and pairs of retaining members on said conveyer for carrying the material, one member of each pair supporting material on the upward movement and the other member supporting the material on the 105 downward movement.

8. In an apparatus of the character described in combination, a vertical conveyer, means for intermittently feeding material to said conveyer, means for moving said 110 conveyer intermittently at each operation of said feeding means, and means for removing the material from said vertical conveyer at the opposite side thereof and at substantially the same level as said feeding means. 115

9. In an apparatus of the character described in combination, a substantially vertical conveyer, means for supplying material to the lower end of said conveyer and means for removing the material from said vertical 120 conveyer at the opposite lower side thereof, and pairs of retaining members on said conveyer for carrying the material, one member of each pair supporting material during the upward movement and the other member 125 supporting the material during the downward movement.

10. In an apparatus of the character described in combination, a substantially vertical conveyer, intermittently movable means 130

for delivering material to said conveyer, a clutch for said conveyer thrown into operation by the movement of said intermittently movable means and a trip device for throwing out said clutch after said vertical conveyer has moved one step forward.

In testimony whereof I have hereunto

signed my name in the presence of the two subscribed witnesses.
